UNITED STATES PATENT OFFICE.

EDMOND R. COOK, OF SACRAMENTO, CALIFORNIA, ASSIGNOR OF ONE-HALF
TO WARREN F. DREW AND MOSES M. DREW, OF SAME PLACE.

CARBURETOR.

SPECIFICATION forming part of Letters Patent No. 531,779, dated January 1, 1895.

Application filed April 20, 1894. Serial No. 508,339. (No model.)

To all whom it may concern:

Be it known that I, EDMOND R. COOK, a citizen of the United States, residing at Sacramento, county of Sacramento, State of California, have invented an Improvement in Carburetors; and I hereby declare the following to be a full, clear, and exact description of the same.

My invention relates to the class of carbureting devices especially adapted for use in connection with gas or explosive engines.

My invention consists of the constructions and combinations of devices which I shall hereinafter fully describe and claim.

In the accompanying drawings, Figure 1 is a vertical section of my carburetor. Fig. 2 is an enlarged view of the regulating valve seat and guides. Fig. 3 is an elevation of the regulating valve. Fig. 4 is a top view of the gratings in the mixing chamber. Figs. 5 and 6 are details to be referred to.

A is the chamber in which the air and gas are mixed. This is divided by a vertical partition α into two compartments α' and α^2 communicating below at α^3 . With compartment α' the air inlet pipe B communicates, and with compartment α^2 the pipe C to the engine connects. Upon pipe B is the valve casing D, shown in detail in Fig. 2. It consists of a valve seat d , and lower and upper guides d' for the stem e of the valve E. This valve is the regulating valve and is shown in detail in Fig. 3. Its body has a conical base and its upper portion has formed in it the grooves e' which taper downwardly both in depth and width. The valve moves up to its seat to close and down to open the passage, and it is obvious that, on account of the tapering grooves e' , the passage will be opened more, the farther down the valve moves, and will be contracted as the valve moves up. The valve seat d is formed with a central raised flange d^2 , which forms an annular chamber in said seat, the object of which will be hereinafter explained.

The valve E is normally held up to its seat by means of the lifting rod F, which is controlled by the spiral spring G. This rod passes through a sleeve H lying within the air inlet pipe B, and dependent from its top. The lower end has a cap h having perforations h' .

The spring G bears above on a collar on rod F and below in a plate g (see Figs. 5 and 6) supported by side pins g' on the fork of a bell crank lever g^2 pivoted at g^3 , and having its vertical arm impinged upon by a setting screw g^4 , by means of which the tension of the spring G can be regulated and restored as needs may require.

Secured upon the lower end of the rod F, directly below the cap h , is a disk or flange f which may be a flat one, but is preferably concaved or cup-shaped as shown. It lies well exposed in the air inlet pipe B.

Above the valve casing D is the connection I from the source of oil, and into this connection is fitted the screw stem J which lies just above the stem of the regulating valve.

In the compartments α' and α^2 of the mixing chamber A are placed small rocks K, or other suitable loose packing freely pervious to gas, said packing being held in place by the gratings L.

A screw stem M passes up through the base of chamber A and lies under the lower end of rod F, serving to limit its downward movement.

N is a cock controlled air inlet to the base of the mixing chamber.

The operation of the device is as follows: The oil is supplied through connection I, and passing down into the valve casing D is checked by valve E, which is itself normally held closed by the spring-actuated lifting rod F. Heated air is drawn into pipe B and passing downwardly, as shown by the arrows, strikes the disk f on the lower end of the rod F. It presses down said disk which draws down its rod, and the valve E being thus relieved drops down, and the oil passes it and flows down into the vaporizing chamber formed by sleeve H. This sleeve being exposed to the heated air in pipe B is itself made sufficiently hot to vaporize the oil within it, a result which is increased by the spreading out of the oil as it flows down over the spring G and is directed outwardly in comparatively thin sheets against the walls of the sleeve, by the coils of said spring. The vapor passes out through the perforations in cap h as is shown by the arrows, and mingles with the air in chamber A. The cup shape of the disk f

serves to catch whatever drip there may be and to spread it out to the action of the air to vaporize it. The mixture of air and vapor now passes down through the packing K by which its component parts are more thoroughly mixed, and the gas rendered lighter, if necessary, by more perfect vaporization due to contact with the heated packing. The necessary fresh air is supplied to the mixture through inlet N. Now, it will be observed that this operation is wholly automatic and the mixture is regulated to the needs of the engine, both in volume and proportions. The inrush of air to pipe B is effected by the sucking of the engine and the volume and force of this air are wholly dependent upon the engine. Therefore, when a large quantity of air is drawn in, it acts to lower the valve E to a greater extent, and this feeds more oil by means of its tapering grooves, and, consequently, the amount of gas formed is commensurate with the volume of air. When less air is drawn in, the valve E is not opened so far and less oil is supplied, less gas is formed and the mixture is still proportionate and is proper for the requirements of the engine.

The object of the annular chamber around the valve seat is to provide a receptacle for sediment, so that foreign substances shall not pass into and clog the valve.

The object of the upper screw stem J is to permit the regulating valve E to be opened by hand, whenever it may be necessary to let some oil down, as at the beginning.

35 The lower screw stem M forms an adjustable stop for limiting the movement of the regulating valve E.

Having thus described my invention, what I claim as new, and desire to secure by Letters 40 Patent, is—

1. In a carburetor for explosive engines, a mixing chamber communicating with the engine, an air inlet communicating with said mixing chamber, a sleeve in said air inlet forming a vaporizing chamber exposed to the inrushing air and communicating with the mixing chamber, a normally closed spring controlled valve for feeding oil to the vaporizing chamber and a means actuated by the inrushing air for operating said valve substantially as herein described.

2. In a carburetor for explosive engines, a mixing chamber communicating with the engine, an air inlet communicating with said mixing chamber, a sleeve in said air inlet forming a vaporizing chamber exposed to the inrushing air and communicating with the mixing chamber, a normally closed spring actuated valve for feeding oil to the vaporizing chamber and a means actuated by the inrushing air for operating said valve, consisting of a spring-controlled rod within said sleeve bearing on the valve and having a disk with which the air comes in contact said rod having the coils of its spring serving as conductors for spreading the oil outwardly and directing it in thin sheets against the walls

of the sleeve whereby vaporization is accelerated substantially as herein described.

3. In a carburetor for explosive engines, a 70 mixing chamber communicating with the engine, an air inlet communicating with said mixing chamber, a vaporizing chamber exposed to the inrushing air and communicating with the mixing chamber, a valve for feeding the oil to the vaporizing chamber, and adapted by its movement to regulate the supply of oil, a spiral conductor in said vaporizing chamber for directing the oil outwardly in thin sheets against the inner walls of the 80 vaporizing chamber and a means, actuated by the inrushing air for operating the valve to regulate said supply, substantially as herein described.

4. In a carburetor for explosive engines, the 85 combination of the valve having a stem projecting above and below, and having the tapering grooves for regulating the feed of the oil, a valve casing consisting of a valve seat with a central raised rim, and the upper and 90 lower guides for the stem of the valve, and a means actuated by the indrawn air for operating said valve, substantially as and for the purpose described.

5. In a carburetor for explosive engines, the 95 combination, of the valve having a stem projecting above and below, and having tapering grooves for regulating the speed of the oil, a valve casing consisting of a valve seat with a central raised rim, and upper and lower 100 guides for the stem of the valve, the inlet pipe for the indrawn air, a sleeve in said pipe forming a vaporizing chamber, the lifting rod, the spring surrounding the same whereby the rod holds the valve to its seat, and a disk or flange 105 on the rod exposed to the indrawn air whereby the rod is moved to permit the valve to open, substantially as herein described.

6. In a carburetor for explosive engines, the combination of a mixing chamber, an inlet 110 pipe for the indrawn air, a sleeve forming a vaporizing chamber exposed within the inlet pipe and communicating with the mixing chamber, a regulating valve controlling the communication between the oil supply and the vaporizing chamber, the lifting rod in the vaporizing chamber having the spiral spring therein and adapted to control the regulating valve, said spring also serving to conduct the oil outwardly in thin sheets against the inner 120 walls of the sleeve, and the flange or disk on the lifting rod exposed within the air inlet pipe, substantially as herein described.

7. In a carburetor for explosive engines, the combination of the air inlet pipe, the sleeve 125 exposed therein, a valve for feeding the oil to the sleeve, the movable rod in the sleeve for controlling the valve and the spiral spring for actuating the rod and serving also as a channel for directing the oil outwardly to the walls 130 of the sleeve, substantially as herein described.

8. In a carburetor for explosive engines, the combination of the air inlet pipe, a sleeve

forming a vaporizing chamber exposed therein, the regulating valve in line with the sleeve for feeding the oil thereto, the spring-controlled rod for controlling said valve and 5 whose spring serves as a means for conducting the oil outwardly against the inner walls of the sleeve, and the upper screw stem for opening the valve by hand, substantially as herein described.

10. In a carburetor, the combination of the air inlet, the sleeve forming a vaporizing chamber exposed therein, the regulating valve for feeding the oil thereto, the rod for controlling said valve, a spring surrounding said rod 15 and serving as a means for conducting the oil outwardly against the inner walls of the sleeve and the disk or flange on the lower end

of the rod below the lower end of the sleeve, made cup-shaped or concave to serve as a drip receptacle, substantially as described. 20

10. In a carburetor, the spring G within the vaporizing chamber, in combination with the tension regulating mechanism, consisting of the plate in which the spring rests, the perforated cap h in which the plate is mounted 25 the pivoted bell-crank having forks supporting said plate and the set screw impinging on the bell crank, substantially as described.

In witness whereof I have hereunto set my hand.

EDMOND R. COOK.
